UNITED STATES PATENT OFFICE.

ANTHONY C. FALLACE, OF BRIDGEBORO, NEW JERSEY.

PUZZLE.

1,257,205.

Specification of Letters Patent. Patented Feb. 19, 1918.

Application filed August 28, 1917. Serial No. 188,553.

To all whom it may concern:

Be it known that I, ANTHONY C. FALLACE, a subject of the King of Italy, residing at Bridgeboro, in the county of Burlington and State of New Jersey, have invented certain new and useful Improvements in Puzzles, of which the following is a specification.

This invention relates to puzzles and more particularly to that type of puzzles which have movable players or parts that are first arranged in a certain position, after which the attempt is made to maneuver them so as to place them in the desired position.

The object of this invention is to provide a puzzle board which will be constructed of a strong material, so that it will not be damaged if it is dropped on the floor.

Another object is to provide a game board, preferably star shaped, which is provided with inverted T-shape slots in its upper surface, and which also has movable players which may be moved from one place to another, until the desired arrangement is had.

Another object is to provide a puzzle which will be of a patriotic nature, which will afford considerable fun and excitement to persons trying to solve it.

Other objects will appear as the description proceeds.

30 In the accompanying drawings:

Figure 1 is a top plan view of my puzzle showing the players in initial position.

Fig. 2 is a similar view showing the puzzle in solved position.

35 Fig. 3 is a sectional view of my game board, showing the inverted T-shape slots in its upper surface.

Fig. 4 is a perspective view of one of the players.

40 In carrying out my invention, I employ a suitable board 1, which is preferably star shape and constructed of metal or some hard material. Inverted T-shape channels 2 are formed around the periphery of the star shape body 1, and have cross channels 3 connecting them. Plugs or stops 4 are placed in one side of each of the points 5 of the star shape body 1, at points adjacent the inner part of said body.

45 A circular slot or T-shape groove 6 is cut in the center part of the body 1 and connects at point 7 with one of the slots 3. It will be seen that a plug or stop 8 is placed in the circular slot at a point near where it connects with the groove or channel 3.

The playing members or sliders 9, are

nine in number and are provided with shanks 10 and reduced portions or smaller heads 11, which travel in the inverted T-shape slots or channels 2 and 3. These nine 60 playing members are divided so that there are three red colored members, three white colored members and three blue colored members.

In playing the game or solving the puzzle, 65 the sliders or playing members 9 are positioned on the board 1, so that there will be one located at the end of every point, except one, and one located at the five places where the five points converge, also so that 70 no two like colors will be next to each other.

It will be understood that the players may be moved around, and that there is only one correct manner in which to operate the players to form them into the position desired. 75

The puzzle is to move the players so that there will be formed the colors of the American flag. There are to be three sets of colors, so that there will be the three sets 80 separately and distinct, and not the three reds, the three whites and the three blues together.

With a little practice and patience this puzzle may be correctly solved, and it will 85 afford much amusement, especially at times when patriotic things are in order.

I have described the slots or channels as inverted T-shape, and set in the board. They may be, however, any desired shape 90 and elevated if it is thought best.

It will be understood that I have not limited myself to any one point, and that minor changes in detail may be resorted to, without departing from the spirit of the invention. 95

Having thus described my invention what I claim as new and desire to secure by Letters Patent of the United States is:

1. A game board, comprising a star-shape 100 member, slots around its periphery, slots connecting said peripheral slots, a circular slot, said circular slot being connected at a point with said slots connecting the peripheral slots, and movable players in the 105 slots, as herein before described.

2. A game board, comprising a star-shape member, slots or channels around its periphery, slots connecting said peripheral slots or grooves, plugs or stops in said slots 110 at points where the sides of the star points intersect, a circular channel having connec-

tion with the before-mentioned slots, and provided with a stop or plug at a point near where it connects with said connecting slots.

3. A game board, comprising a star-shape member, as claimed in claim 1, all of the slots or channels being of inverted T-shape, and movable playing members of different colors, having a reduced shank and a smaller

head portion, adapted to slide in the inverted T-shape channels.

In testimony whereof I affix my signature in the presence of two witnesses.

ANTHONY C. FALLACE.
